STRIP SEPARATING DEVICE

Walter J. Rudolph, Chicago, Ill., assignor, by
mesne assignments, to Acme Visible Records,
Inc., Chicago, Ill., a corporation of Delaware

Application March 16, 1938, Serial No. 196,159

6 Claims. (Cl. 164—84.5)

This invention relates to improvements in a machine for separating flexible visible index strips from a sheet thereof, and refers specifically to a machine which cleanly separates said strips and discharges the separated strips in an orderly manner whereby the same may be conveniently handled in removing them from the machine and in subsequently inserting them in appropriate frames.

10 Flexible visible index strips such as those described in United States Patent No. 1,594,112 are well known and widely used. Flexible index strips of this type are provided in continuous sheet form comprising wood veneer faced on the 15 front and back with paper. The laminated sheet thus formed is then partially severed in the direction of its thickness or depth to permit subsequent separating into individual resilient index strips. The sheet while in partially severed condition, of course, is sufficiently coherent to be 20 passed, for instance, around the platen of a typewriter whereby the index matter is typed upon the individual strips. Thereafter, the strips are severed completely and inserted in appropriate frames provided for that purpose.

Certain industries, bureaus and the like use 25 thousands of these strips, as for instance, telephone companies, mail order houses, electric power companies and many other instances of extensive use may be cited. In most cases these index records are periodically supplemented, altered or otherwise changed, requiring the preparation of new strips. Heretofore, after the strips were typed they were manually separated, 30 which, as can readily be appreciated, takes time where thousands of such strips are being handled.

My invention is particularly directed to the provision of a machine which automatically separates the strips, the typed partially severed sheet being fed into the machine and the strips being delivered from the separating mechanism in separated parallel alignment, the strips upon delivery all occupying the same relative position 45 as they did when in sheet form.

Briefly described, my invention comprises a plurality of traveling belts which, in addition to passing over a plurality of suitable pulleys to change the direction of travel of the belts, pass 50 around a plurality of sleeves or drums, the sheet of partially severed strips being carried by said belts over said sleeves or drums whereby the sheet is bent along the various lines of severance, first in one direction and then in the other, the last 55 bending operation subjecting the unsevered por-

tions of the sheet to tension whereby complete severance occurs.

Other objects and advantages of my invention will be apparent from the accompanying drawings and following detailed description. 5

In the drawings, Fig. 1 is a plan sectional view of my machine.

Fig. 2 is a sectional view taken on line 2—2 of Fig. 1 with the cover housings in place.

Fig. 3 is a transverse sectional view taken on 10 line 3—3 of Fig. 1.

Fig. 4 is a transverse sectional view taken on line 4—4 of Fig. 1.

Fig. 5 is a longitudinal sectional view of a 15 partially severed sheet of index strips.

Fig. 6 is a similar view of the separated strips as delivered from my machine.

Fig. 7 is a slightly enlarged detail sectional view of the strip separating mechanism.

Fig. 8 is a transverse sectional view similar 20 to Fig. 4, illustrating a delivered sheet of completely separated strips, and the manner in which the delivered strips may be removed from the machine.

Fig. 9 is a sectional view of a tray for removing 25 the separated strips from the machine.

Referring in detail to the drawings, 1 indicates a relatively flat bottom or base, the opposite longitudinal edges of which are bent to provide channels 2 which are coextensive with the length 30 of the base 1. Feet 3, which may take the form of inverted rubber vacuum cups, are secured adjacent each corner of the base 1 by means of bolts 3' which pass through the bottom portion of the channels 2 and are retained by nuts 4. 35

A frame 5 of relatively heavy material is removably secured, preferably by bolts (not shown), to the inner face of each of the channels 2 adjacent one end of the base, said frames extending upwardly at right-angles to the plane of the 40 base. Struts or tie-rods 6 serve as spacers and supports for the upper portions of the opposite frames 5, the struts being provided with downwardly extending lugs or fingers 7 which embrace the upper edges of the frames adjacent the 45

opposite end of the base 1. Frames 8 are mounted, similar to frames 5, upon the inner surfaces of channels 2, said frames being spaced and supported by a tie-rod 9, identical with tie-rods 6. 50

A housing 10 is positioned over the frames 5, said housing having a top 11, side walls 12 and 13 and end walls 14 and 15. The side walls 12 and 13 telescope the outer surfaces of channels 2 on each side and are secured to said channels 55

by screws 16 or the like. A portion of the top 11 of the housing between the frames 5 extends downwardly along an inclined plane, as shown best at 17 in Fig. 7, said inclined portion being 5 provided with a relatively large aperture. Another portion 18, of the top, extends vertically downwardly and is joined with the lowermost extremity of the inclined portion 17, as indicated at 19. A guard 20 is joined to the member 18 10 and is disposed along an inclined plane substantially parallel to inclined portion 17. Between the guard 20 and the inclined portion 17, an opening 20' is provided whereby a sheet 21 of partially severed index strips 22 may be inserted into the machine, as will be hereinafter more fully described. The end wall 14 of the housing is imperforate, but the opposite end wall 15 is provided with an opening 23, the purpose of which will be hereinafter described.

20 Each frame 5 is provided, adjacent one end, with a pair of elongated slots 24 and 25, the slot 24 being located immediately above the slot 25. A bearing plate 26 is adjustably mounted, by means of screw 27 adjacent slot 24, the shank of screw 27 passing through a slot 28 provided in the bearing plate. A similar plate is mounted adjacent the slot 24 in the opposite frame. A shaft 29 is journaled in the opposite plates 26, said shaft extending through opposite slots 24. 25 A roller 30 is carried by shaft 29 between the frames 5. It can readily be seen that by proper adjustment of the bearing plates 26, shaft 29 can be disposed in any desired position along the length of slots 24.

30 A bearing plate 31 is positioned adjacent each slot 25 and is secured to each opposite frame 5 by means of a screw 32, the shank of which passes through a slot 33 provided in each plate 31. A shaft 34 is journaled in each opposite plate 31, said shaft extending through each slot 25. A roll 35 is carried by shaft 34 between the opposite frames. Similar to roll 30, roll 35 may be adjusted a distance limited by the length of slots 25.

35 A slot 36 is provided in opposite frames 5 and a bearing plate 37 is positioned adjacent each slot, a plate 37 being secured to each opposite frame 5 by means of a screw 38, the shank of which passes through a slot 39 provided in the plate 37. A shaft 40 is journaled in each plate 37 and extends through slots 36 whereby said shaft may be adjusted along the length of the slot. Shaft 40 carries a roll 41.

40 A shaft 42 is journaled in opposite frames 5 and carries a roll 43 between said frames. Similarly, a shaft 44 is journaled in said frames and carries a roll 45.

45 A shaft 36 is also journaled in the opposite frames 5 and carries adjacent one end thereof, exterior of the frame, a gear 47. A crank 48, having a handle 49 is mounted upon the end of shaft 46 whereby the same may be manually rotated. Shaft 46, between frames 5, is knurled, as indicated at 50 in Fig. 1, along spaced portions of its length, and intermediate said knurled portions freely rotatable sleeves 51 are carried.

50 A shaft 52 is journaled in opposite frames 5 and carries at one end thereof a gear 53 which meshes with gear 47 and is rotated therewith when crank 48 is manipulated. Intermediate frames 5, shaft 52 is formed, along spaced portions 54 of its length, with hexagonal cross-section. Of course, as the description proceeds it will be appreciated that said portions may be of 55 triangular, square, pentagonal or octagonal sec-

tion, in short, my invention broadly contemplates spaced portions of polygonal section. Intermediate the polygonal portions 54, shaft 52 carries freely rotatable sleeves 55.

At the opposite end of the machine the frames 5 5 are provided with slots 56 through which shaft 57 extends, said shaft being journaled in bearing plates 58 adjustably secured to frames 8, in a manner similar to the relationship of plates 26, 31 and 37 to frames 5. Frames 8 are also provided with opposite slots 59, through which shaft 60 extends, said shaft being journaled in plates 61 which are adjustably secured to the sides of frames 8. Intermediate frames 8 shaft 57 carries a roll 62, and similarly shaft 60 carries a roll 63. 15

An endless conveyor belt 64, preferably constructed of elastic tape or the like, is trained, in the order named, around the following rolls and shafts; a knurled portion 50 of shaft 46 whereby the belt is driven, a polygonal portion 54 of shaft 20 20, over roll 45, around roll 63 at the opposite end of the machine, back under the lower portion of roll 45, around rolls 35 and 30, and under roll 41 to shaft 46. A similar belt 65 at the opposite side of the machine follows a similar path 25 although spaced from belt 64.

A similar conveyor belt 66 is trained around the following rolls and sleeves in the order named: around a sleeve 51 on shaft 46, around a sleeve 55 on the shaft 52, over roll 45, around 30 roll 62 at the opposite end of the machine, over roll 43, around roll 41 and back to sleeve 51. In traveling from one end of the machine to the opposite end thereof in the direction indicated by the arrows, belts 64 and 66 are disposed adjacent 35 and parallel. Similarly a belt 67, which follows the same path as belt 66, is disposed adjacent and parallel to belt 65.

Conveyor belts 68 and 69, constructed of the same material comprising belts 64, 65, 66 and 67, 40 follow similar paths and will be traced together, although the belts move in spaced relationship. Said belts are trained around rolls 35 and 30, under roll 41, around knurled portions of shaft 45, around polygonal portions of shaft 52, around 45 roll 45, and back to roll 35.

A conveyor belt 70 travels around the central portion of roll 41, over a sleeve 51 on shaft 46, around roll 43 and back to roll 41.

As has been hereinbefore described, the purpose of my machine is to automatically completely separate partially severed sheets 21 of index strips. In the construction of the sheets 21 the lower facing 21a is usually the portion which remains unsevered and sometimes a very small 55 portion of the central core is unsevered. If an attempt is made to separate the strips 22 by merely exerting a lateral pulling force, it will be found that it is not only difficult but a ragged edge frequently results, which, of course, is undesirable since the strips will not lie satisfactorily in the index frame. If the strips are severed by bending the sheet acutely in a concave-upwardly direction, as viewed in Fig. 5, ragged edges will also result. To properly sever the 65 strips, the sheet is acutely bent concave-downwardly to first fold the unsevered layer 21a; the sheet is then acutely bent in the opposite direction whereby the unsevered portion thus preparatory folded, separates cleanly.

In utilizing my invention a sheet 21 is inserted in the feed opening 20' with the lines of severance substantially at right angles to the direction of feed and with the unsevered layer 21a facing downwardly. The angular relationship of 75

the travel of the belts 64, 68, 69 and 65 from roll 30 to roll 41, causes said belts to pass through the opening in the inclined member 17. The sheet is therefore deposited upon the upper surfaces of said belts all of which are driven from shaft 46. As said belts pass beneath roll 41, belts 66, 70 and 67 are brought to a riding position on top of the sheet. In traveling between roll 41 and shaft 46 the sheet is confined between belts 64, 65, 68 and 69 on the bottom, and belts 66, 70 and 67 on top. However, before wrapping around shaft 46, belt 70 leaves the sheet and returns around roll 43, the remaining belts then carry the sheet around shaft 46, which, having a relatively small radius of curvature, acts to acutely bend the sheet, hinging the strips about the unsevered layer 21a and preparatorily folding said layer along the intended lines of severance.

20 The sheet, confined between belts 64, 65, 68 and 69 and belts 66 and 67, is then carried to shaft 52. Said belts in carrying the sheet around shaft 52 flexes or hinges said sheet in the opposite direction as each strip 22 tends to ride upon a flat side of the hexagonal portions 54. The layer 21a being flexed in this direction is thereby severed since it is subjected to tension, and individual strips now pass from shaft 52 in seriatim between said belts. When the now severed sheet reaches roll 44, belts 68 and 69 return around roll 45 and the strips are carried forwardly between belts 64 and 65 on the bottom and belts 66 and 67 on top until said strips reach the position shown in Fig. 1, at which time the cranking operation is discontinued.

35 In the event that relatively wide strips 22 are employed, instead of maintaining the shaft 52 hexagonal and increasing its average radius of curvature so as to have the sides of the hexagon conform with the width of the strips, I prefer to retain a shaft of smaller radius of curvature and decrease the number of sides of the polygon to, for instance, a pentagon, a square or even a triangle.

40 It will be noted that belts 64, 65, 68 and 69 are driven by the high frictional contact of the knurled surfaces of shaft 46 and the polygonal sections of shaft 52, whereas belts 66 and 67 are only driven by the relatively frictionless grip of 45 the sleeves upon shafts 46 and 52, and the friction caused by the interpositioned sheet or strips. By 50 this arrangement belts 66 and 67 can readily move relative to belts 64, 65, 68 and 69. Such movement may take place, for instance, when the 55 first strip of a fed sheet 21 does not register with a side of the polygonal sections of shaft 52, in which case belts 66 and 67 may move forwardly or rearwardly relative to belts 64, 65, 68 and 69 until proper registration is secured. Again, relative movement of belts 66 and 67 with respect to 60 belts 64, 65, 68 and 69 when a sheet is fed beneath roll 41 with the lines of severance of the strips not parallel to the axes of rolls 41 and 46. Relative movement of belts 66 and 67 with respect to 65 belts 64, 65, 68 and 69, and relative movement of belt 66 with respect to belt 67 may take place. Of course, by the use of elastic belts the sheet and strips will always be subjected to elastic urging, the urging force never being sufficiently positive 70 to break the fragile strips. Proper tension of the belts may be obtained by adjusting the relative positions of rolls 30, 35, 41, 62 and 63, as has been hereinbefore described.

In view of the fact that the indicia 71 upon the strips is usually typed thereon and the upper

surfaces of the strips are usually white or of a light color, the surfaces frequently being enamelled, the tapes or belts 66, 67 and 70 which contact the upper faces of the strips are preferably such that they will leave no marks on the strips. In addition, all precautions are taken to prevent dust from accumulating on that face of the belts which contacts the upper surfaces of the strips.

8 A housing 72 is provided for rolls 62 and 63 having side walls 73 and 74, and end walls 75 and 76. The side walls 73 and 74 embrace the outer surfaces of the channels 2 and are secured to said channels by screws 77. The side walls and end wall 75 are imperforate, but end wall 76 is provided with openings 78 through which the belts 64, 65, 15 66 and 67 pass.

10 A housing 79, Figs. 4 and 8, covers a portion of the base 1 between housings 10 and 72, said housing 79 being secured to the outer surfaces of 20 the channels 2 by any suitable means. It will be noted that the lower passes of belts 64 and 65 are beneath housing 79 whereas the upper passes of said belts are above said housing.

25 A pair of spaced lugs 80 are mounted upon the housing 79 on the side of the machine opposite to the crank-side, said lugs supporting a pintle or shaft 81. A plate 82 is carried by pintle 81, said plate carrying a right-angled flange 83 which is coextensive in length with plate 82. A coil spring 84 embraces each end of the pintle 81, one 30 end of each of said springs being anchored to the housing 79, as shown at 85 in Fig. 4. The opposite end of each coil spring is anchored upon the right-angle flange 83, said springs normally urging plate 82 in a counterclockwise direction 35 around pintle 81.

30 Of course, it is frequently desirable to insert all of the strips 23 in a suitable frame (not shown) in the order in which said strips are discharged from the separating mechanism, and hence it is 40 desirable to remove all of the separated strips from the belts 64, 65, 66 and 67 at once and preserve their order of position. To accomplish this operation a tray 86 is used which carries a spring-clip member 87 which simultaneously grasps the 45 ends of all of the strips. When the strips are delivered from the separating mechanism in housing 10, the ends of the strips are seldom in perfect alignment. However, by rotating the plate 82 in a clockwise direction to a vertical position, the 50 action of clipping the ends of the strips upon the tray, simultaneously aligns the ends of the strips against the plate 82. The tray carrying the properly aligned strips may then be withdrawn, as indicated in dotted lines in Fig. 8, and the strips 55 may then be inserted in the strip holding frame.

50 In order to prevent the surfaces of the belts 66 and 67 which contact the faces of the strips 22 from becoming soiled or dusty, inverted channels 88 may be positioned over said belts at their upper 60 pass. Channels 88 may be spaced from each other and secured to the housings 10 and 72 by means of spacers 89 and screws 90.

65 Rolls 30, 34, 41, 43, 62 and 63 are provided with suitable circumferential grooves whereby the respective belts carried around said rolls are maintained in proper tracking alignment.

70 Of course, many changes may be made in the structure hereinbefore described without departing from the spirit of my invention, and hence I 70 do not wish to be limited except as necessitated by the prior art.

I claim as my invention:

75 1. A device of the class described which comprises in combination, a frame, a plurality of

shafts positioned in said frame, a plurality of endless belts traveling in parallel relationship around said shafts for carrying a sheet of partially severed index strips, said sheet being carried between at least two of said belts in opposite directions around said shafts to completely separate said strips, the shafts around which said sheet is carried being of sufficiently small diameter to cause said sheet to bend acutely during travel around said shafts.

2. A device of the class described which comprises in combination, a frame, a plurality of shafts positioned in said frame, a plurality of endless belts traveling in parallel relationship around said shafts for carrying a sheet of partially severed index strips, said sheet being carried between at least two of said belts in opposite directions around said shafts, said shafts being of such diameter as to rupture by tension the partially severed portion of the sheet and to completely separate said strips, and means for driving said shafts around which said sheet travels.

3. A device of the class described which comprises in combination, a frame, a pair of shafts journaled in said frame, one of said shafts being substantially round in cross-section and the other of said shafts having portions of polygonal cross-section, a plurality of endless belts traveling in parallel relationship around said shafts for carrying a partially severed sheet of index strips, said sheet being carried between at least two of said belts in opposite directions first around said first mentioned shaft and then around said second mentioned shaft to completely sever said strips.

4. A device of the class described which comprises in combination, a frame, a pair of shafts positioned in said frame, two pairs of endless belts traveling in laterally spaced relationship around said shafts for carrying a sheet of partially severed index strips, said sheet being carried on one pair of belts and beneath the other pair of belts, and being successively carried in opposite directions at substantially right angles 45 to the length of said strips around said shafts

by said belts, the radius of curvature of said shafts being such as to completely sever said strips.

5. A device of the class described which comprises in combination, a frame, a plurality of shafts positioned in said frame, two of said shafts being driven and comprising means for rotating them at equal speeds, a plurality of endless belts traveling in parallel relationship around said shafts for carrying a sheet of partially severed index strips, said index strips being carried between at least two of said belts successively in opposite directions, first in one direction around one of said driven shafts and then in the opposed direction around the second of said driven shafts, each of said driven shafts being of a sufficiently small diameter relative to the width of said carried strips to cause said sheet to be bent acutely around them and thereby to completely separate said strips, means for carrying said strips confined by said belts forwardly in a plane, and means disposed adjacent the path of travel of said strips for aligning the ends of said strips.

6. A device of the class described which comprises in combination, a frame, a plurality of shafts positioned in said frame, only two of said shafts being driven and comprising means for rotating them at equal speeds, a plurality of endless belts traveling in parallel relationship around said shafts for carrying a sheet of partially severed index strips, said sheet being carried between at least two of said belts successively in opposite directions around said driven shafts by first acutely bending said sheet around one of said driven rolls, then returning said sheet to planar formation, and thereafter bending said sheet acutely in an opposed direction around the second driven roll to completely separate said strips, means for carrying said strips confined by said belts forwardly in a plane, and means disposed adjacent the path of travel of said strips for aligning the ends of said strips, said means comprising a plate positioned in a plane at right-angles to the length of said strips.

WALTER J. RUDOLPH. 45
